J. R. GILDA,
NAILING MACHINE,
APPLICATION FILED JAN. 16, 1919.

Patented Apr. 5, 1921.

WITNESS.

INVENTOR.
John R. Gilda,
BY Ralph Dees

HIS ATTORNEY.

UNITED STATES PATENT OFFICE.

JOHN R. GILDA, OF ST. LOUIS, MISSOURI.

NAILING-MACHINE.

1,373,961.

Specification of Letters Patent.

Patented Apr. 5, 1921.

Application filed January 16, 1919. Serial No. 271,425.

To all whom it may concern:

Be it known that I, JOHN R. GILDA, a citizen of the United States, residing at the city of St. Louis, State of Missouri, have invented a certain new and useful Improvement in Nailing-Machines, of which the following is a specification, reference being had to the accompanying drawings, forming a part thereof.

10 This invention relates to nailing machines.

The invention relates particularly to mechanism for straightening warped boards preparatory for the operation of the nailing mechanism, and an object of the invention is to provide a simple and efficient mechanism for this purpose.

In the accompanying drawings illustrating a satisfactory embodiment of the invention,

20 Figure 1 is a plan view of the mechanism comprising my invention embodied in a nailing machine.

Fig. 2 is a front elevation.

Fig. 3 is a side elevation.

25 As shown, my invention comprises a pair of levers each composed of an arm 1 extending over the table or bed of the nailing machine and an outwardly extended arm 2. The arms 2 are mounted upon studs 3. The arms 1 have hooks 4 on their inner sides adapted to engage the edge portions of a warped board and to straighten the board preparatory for operation of the nailing mechanism. Also, each of the arms 1 is provided with a vertical pin or projection 5. The pins or projections 5 engage the side edges of the horizontal board, the end of which is placed upon the end of the warped board preparatory for operation of the nailing mechanism. By the pins or projections 5 the horizontal board is properly positioned with the side edges thereof even with the side edges of the warped board shown at A in Fig. 1, while at the same time the warped board is straightened against the back part of the nailing machine.

50 Each of the angular levers above described supports a roller 6 at the angle thereof. The rollers 6 extend into the channel between the longitudinal flanges of a channel member 7 so that when the channel member is moved rearwardly, the levers, which through their connecting rollers 6 are substantially rigid relatively to the channel 7, will also be moved rearwardly. In such rearward movement, the interposed board will be first en-

gaged upon its outer face and at its opposite side edges by the hook-ends of the levers and the board then drawn substantially flatwise against the back or support of the nailing machine. Through such action of the levers, the warped board will be straightened, and at the same time the levers, through the pins 5, will properly position the horizontal board thereon.

65 The operating mechanism for moving the channel member comprises two arms 8 of angular formation as shown in Fig. 1, having their ends connected to the channel member 7 and having slots 9 through which a rock shaft 10 extends. A spring 11 connects each of said arms 8 with a stationary part of the machine so that the angular arms 1-2 are thereby normally held in the positions shown in Fig. 1, ready for operation to straighten a warped board.

70 The shaft 10 supports a cam 12 between the arms 8, and said arms 8 support a roller 13 against which the cam operates when the rock shaft 10 is turned in the direction indicated by the arrow in Fig. 3. The shaft 10 is arranged to be rocked or turned in the direction of the arrow just prior to the operation of the nailing mechanism, so that the arms 8 will be moved and the angular arms 1-2 will also be moved to straighten the warped board just prior to the operation of the nailing mechanism at each operation of the machine. As shown, the shaft 10 is one of the usual rock shafts of the machine 80 and is provided with the usual connections 14 by which said shaft is rocked or turned in the manner described before each operation of the nailing mechanism.

85 In this particular type of nailing machine 95 I am enabled to make use of one of the usual rock shafts though it will be apparent that the benefits of my invention are by no means restricted to use in a machine having such a rock shaft initially embodied therein. 100 It is perfectly apparent that the invention may be used with equal advantage in machines which do not initially contain the rock shaft 10 and that such shaft or its equivalent may be added to the machine not 105 initially containing it in order to enable my invention to be satisfactorily used.

90 As shown the roller 13 is supported upon an axial bolt 15 which may be held in different positions by adjusting screws 16. 110 Thus the roller 13 may be adjusted and retained in different positions relative to the

cam 12, thereby varying the extent of movement of the arms 8 and also extent of movements of the arms 1-2.

Under present conditions in which the difficulty of obtaining well seasoned and straight boards for use in the manufacture of boxes is well known, the advantage of my invention is apparent. By its use boards which are warped so that they could not otherwise satisfactorily be used may be rapidly and satisfactorily straightened while in the nailing machine before operation of the nailing mechanism, so that when the nails are driven they will pass properly through the horizontal board placed upon the warped board and into the warped board while it is held straight by the angular levers 1-2. The nailing machine may be operated as rapidly as it could be operated upon straight boards, and the boxes or parts made by the machine have an appearance of perfection which is not modified when they are removed from the machine after the parts have been nailed together.

It will be apparent that the specific construction of the mechanism may be modified in various particulars without departing in the least from the spirit and scope of the invention. I do not confine myself to unessential features, but what I claim and desire to secure by Letters Patent of the United States, is:—

1. A nailing machine including, in combination with a support, a bar mounted for movement relatively to the support, a pair of spaced hooked levers mounted on the bar to engage at its opposite side edges the outer face of a warped board placed therebetween, and means having engagement with the bar for positively pulling the same to cause the levers to engage and draw the board substantially flatwise against the support for straightening the board.

2. A nailing machine including, in combination with a support, a pair of spaced levers arranged to receive a warped board between them, hooks on said levers arranged to engage the side edges of the board, a rock shaft, a cam on said shaft, and arms actuated by said cam for moving said levers to straighten the warp board against the support.

3. A nailing machine including, in combination with a back support for supporting a warped board, a pair of levers arranged to engage the side edges of the board, a channel member, rollers on said levers engaging in the channel of said member, arms connected to said channel member for moving the same, a rock shaft, and a cam on said rock shaft

for moving said arms to cause said levers to engage and straighten the board against the support.

4. A nailing machine including, in combination with a back support for supporting a warped board, a pair of levers arranged to engage the side edges of the board, a channel member, rollers on said levers engaging in the channel of said member, arms connected to said channel member for moving the same, a rock shaft, a cam on said rock shaft for moving said arms to cause said levers to engage and straighten the board against the support, and springs on said arms for moving said arms and thereby said levers to their initial positions.

5. A nailing machine including, in combination, a back-support for supporting a warped board, a pair of spaced rigid levers arranged to receive the warped board between them, hooks on the levers adapted to engage the outer face of the warped board at its opposite side edges, means for actuating the levers to engage and press the board to straight position against the back support, and members carried by the levers for alining a second board relatively to the warped board when straightened.

6. A nailing machine comprising in combination a pair of levers, a back support for a warped board, a channel member, rollers on the levers engaging in the channel of the channel member, springs normally holding said levers out of position to engage the warped board, and mechanism for operating the levers to engage the warped board and press the same to straight position.

7. A nailing machine comprising, in combination, a back support for a warped board, a pair of levers operable to engage and press the board to straight position against the back support, arms for operating said levers, a rock shaft, a cam on said rock shaft, and a roller supported by said arms in position to be engaged by said cam whereby said levers will be operated as an incident to the turning of said rock shaft.

8. A nailing machine including, in combination, a support for a board, a pair of spaced levers for drawing a warped board against the support for straightening the board, means for actuating the levers, and pins carried by the levers for alining a second board with the warped board when straightened.

In testimony whereof, I have signed my name to this specification.

JOHN R. GILDA.
